graphie m. b. H., Berlin, Germany, a corpora-
tion of Germany

Application June 18, 1937, Serial No. 148,861
In Germany July 22, 1936

13 Claims. (Cl. 250—17)

The invention relates to an arrangement for controlling the transmission of ultra-short wave high-frequency energy passing from a generator to a load, more especially to an antenna across a concentric tubular line.

5 When modulating an ultra-short wave transmitter, it is known that the necessary condition of operating outside the so-called disruption region can only be fulfilled under difficulties. Owing partly to the instability of the resonant circuits, and partly to the fact that the electrons have only a finite velocity, the conditions for building up a satisfactory modulating system for application to ultra-short waves, are no longer as simple as in the case of longer waves. It is 10 very difficult, therefore, to modulate the transmitter proper by influencing its operating conditions. Furthermore, in using ultra-short waves, it should also be borne in mind that the excited transmitter wave depends to a greater or lesser degree on the operating state of the transmitter so that if the feed potentials are varied, the desired amplitude modulation is accompanied in a greater or lesser degree by an 15 undesired frequency modulation.

20 In order to avoid these difficulties, various methods have hitherto been proposed aiming at a control of the high-frequency energy outside the actual generator and independent of the 25 conditions of excitation of the transmitter oscillations. Thus, the energy already radiated can, after having left the antenna, be subsequently modulated, for instance, by causing the waves to pass through a layer of ionized gas whose 30 degree of ionization is varied in the rhythm of the modulation, and which thus permits at one time the passage of a greater amount of radiation energy and at another time a smaller amount, or absorbs this amount of energy. Since 35 the size of the gaseous layer is to be large as compared with the wave length, this method can be employed only for extremely short waves. It appears, therefore, to be a better and simpler method to catch the high-frequency oscillations 40 on their way from the oscillation generator to the antenna, namely in the antenna feed line. To this end, variable high-frequency resistors which can be influenced to a large extent in a manner free of inertia, are inserted in the transmission line and which block the passage of the high- 45 frequency energy passing from the generator to the antenna, or render such passage difficult, or permit the passage at an optimum efficiency. For 50 such variable resistances, glow tubes are found to be well suited, since the amplitude of the 55

electron discharge therein may be controlled in the rhythm of the modulation to be impressed upon the transmitter oscillations. If such a glow tube is placed between the two wires of a Lecher system, the ionized gas exerts a detuning action, as well as an energy absorbing action upon the Lecher line, thus influencing amplitude of the oscillations radiated by the antenna, in accordance with the varying conditions of ionized gas.

60 The hitherto known practical embodiments of this method are such that a glow discharge tube of elongated shape, for instance of the type employed in oscilloscopes, is placed directly between the two Lecher wires extending from transmitter to the antenna, at which place it acts in part as capacitive lateral resistance between the Lecher wires with a dielectric fluctuating in its special extent, as well as in its density in the rhythm of the modulation, and acting on the other hand 65 as an energy consuming, and as a variable damping resistance. In order to exploit as much as possible the detuning, and damping action of the ionized gas, it is advisable in addition to using solely the Lecher wires as layers for the gaseous 70 condenser, to enlarge the surface of said gas by means of special metallic layers in contact with the Lecher wires. These layers on the other hand entail the disadvantage that they increase 75 the residual capacity which prevails when the glow tube is not ignited. As a result thereof, the optimum transmission of energy to the antenna will be disturbed, and the upper limit of the control range will be decreased. In practice 80 therefore, a compromise must be made between the two required conditions one of which is to employ the largest possible condenser layers, and the other of which is to obtain the lowest possible initial capacity. Such a compromise, however, 85 is opposed to the operation of the transmitter at highest efficiency.

90 The present invention overcomes effectively this drawback in that for the transmission of energy from the generator to the load, such as an antenna for instance, a concentric tubular line known as such is used within which the glow tube is so arranged that a concentric glow discharge will be formed between the inner tube and the outer tube. Hence, the entire glow discharge 95 participates in the control of the transmission of energy to the antenna, without the presence of special metal surfaces whereby the capacity per unit length of the line would be varied. Consequently, the efficiency of the transmission will 100

- conductor of said device forming an anode for said device and being arranged in the same straight line as the outer conductors of said two sections of concentric line.
5. A system in accordance with claim 1, characterized in this, that the impedance of said concentric line is matched at its ends to the impedances of said source and utilization circuit.
7. A concentric transmission line having an inner and an outer conductor, a source of high frequency oscillations connected to one end of said line, a utilization device connected to the other end of said line, an electron discharge tube certain electrodes of which are concentric to each other and constitute portions of said transmission line, and means for modulating said high frequency oscillations, said means being operable to vary the impedance of the discharge path in said discharge tube.
10. A concentric transmission line having an inner and an outer conductor, a source of high frequency oscillations connected to one end of said line, a utilization device connected to the other end of said line, a gaseous electron discharge tube certain electrodes of which are concentric to each other and constitute portions of said transmission line, and means for modulating said high frequency oscillations, said means being operable to vary the impedance of the discharge path in said discharge tube.
15. A system in accordance with claim 7 and further characterized in that said electron discharge tube possesses a centrally disposed linear cathode connected to and between different portions of the inner transmission line conductor, and an outer electrode connected to and between different portions of the outer transmission line conductor.
20. A transmission line having coaxial inner and outer conductors, a source of high frequency oscillations connected to one end of said line, a utilization device connected to the other end of said line, an electron discharge tube forming a connecting link between two portions of said line, said tube containing an anode two terminals of which are respectively connected to different portions of said outer conductor, and a cathode two terminals of which are respectively connected to different portions of said inner conductor, and means connected to said anode and cathode through said conductors for varying the impedance of said tube.
25. A transmission line having coaxial inner and outer conductors, a resonant circuit comprising a loop of conductor interconnecting two adjacent ends of the inner and outer conductors respectively, a source of ultra-high frequency oscillations coupled to said resonant circuit, an electron discharge device having at least one electrode which constitutes an interconnecting link between different portions of said line, and means including a connection through one of said conductors for activating said device.
30. Apparatus in accordance with claim 11 and having means for varying the impedance of said electron discharge device, said means serving also to modulate the ultra high frequency energy impressed on said transmission line.
35. A transmission line having coaxial inner and outer conductors, a gaseous discharge tube having an outer electrode which forms an interconnecting link between different portions of said outer conductor, said tube also having a linear cathode which forms an interconnecting link between different portions of said inner conductor, a resonant circuit having a capacitor intercoupling different portions of an inductive loop, said loop portions being connected respectively to the inner and outer conductors, and means for producing a glow discharge in said tube, said means having connections across the terminals of said capacitor.
